UNITED STATES PATENT OFFICE.

AUGUSTUS F. KLASING, OF CHICAGO, ILLINOIS, ASSIGNOR TO THE KLASING CAR BRAKE COMPANY, A CORPORATION OF COLORADO.

BRAKE MECHANISM.

Application filed February 10, 1922. Serial No. 535,457.

To all whom it may concern:

Be it known that I, AUGUSTUS F. KLASING, a citizen of the United States, residing at Chicago, in the county of Cook and State 5 of Illinois, have invented certain new and useful Improvements in Brake Mechanism, of which the following is a specification.

My invention relates to apparatus for the manipulation of brakes of a railway car, 10 the invention being concerned particularly with the type of brake mechanism comprising a power applying device so placed on the wall, the end wall, preferably, of a box car, or in equivalent locations on tank, gondola or flat cars, that the same may be operated with convenience and safety by the trainman, together with a transmitting device for changing the substantially vertical pull exerted by the power applying device 15 to a substantially horizontal pull on the brake rigging underneath the car body.

The principal object of the invention is to provide a new and improved brake manipulating apparatus of this general character which will be inexpensive to manufacture and install, can be applied readily to cars of different size and type, will consist of comparatively few parts of simple and strong construction, and will be capable of 20 first rapidly taking up the slack in the brake connections and then applying the brake shoes with great braking force against the car wheels.

The invention consists of the new and 25 improved arrangements, devices and constructions, to be hereinafter described and claimed, for carrying out the above stated objects and such other incidental objects as will be referred to in the following description of the preferred embodiment of the invention shown in the annexed drawings.

Referring to the drawings,

Fig. 1 is a fragmentary side elevation of one end of a railway box car with the brake manipulating apparatus of my invention installed thereon.

Fig. 2 is a view, in perspective, of the winding drum and its operating lever forming part of the apparatus.

Fig. 3 is a longitudinal sectional view of the winding drum and associated parts.

Fig. 4 is a fragmentary end elevation of

a part of the power applying device arranged on the car wall.

Fig. 5 is a fragmentary sectional view 55 taken on line 5—5 of Fig. 4.

Fig. 6 is a longitudinal sectional view through the part of the apparatus under the car which has been designated the transmission device, and

Fig. 7 is a sectional view on line 7—7 of Fig. 6.

Referring to the drawing, A designates the superstructure of a railway box car on the end wall of which the part of the apparatus which has been designated the power applying device is preferably arranged. The power applying device is designated as a whole by the letter B. The transmission device, located on the under side of the car, 60 is designated as a whole by the letter C. D is a platform on the end of the car on which the brakeman stands when setting and releasing the brakes. The transmission device C comprises an inverted channel-shaped 65 structure 10 formed with flanges 11 for attachment, by bolts 12, to the floor or under frame of the car. The side members 13 of the channel member 10 are formed with recesses 14 closed to provide grooves by longitudinally arranged members 15 secured to the member 10 by bolts 16. 17 is a drum having gudgeons 18 which enter the grooves 14. The channel member 10 is formed with a pair of spaced racks 19 and the drum 17 70 is provided with gear wheels 20, preferably formed integrally with the drum, adapted to mesh with racks 19. Secured to the drum adjacent the gear wheels 20, for example by tap screws 21, are a pair of take-up chains 75 22 which are connected with the brake rigging (not shown), on the under side of the car. The brake rigging may be of any common type. The chains 22 converge and are attached to the chain or pull rod usually 80 employed for operating the brakes of a railway car; the arrangement of chains 22 being substantially the same as the arrangements of the lower chains shown in Fig. 4 85 of the drawings. The chains 22 are adapted to be wound upon winding surfaces 23 on the drum 17. The drum is formed with a centrally arranged pulley 24, preferably of 90 larger diameter than the diameter of the

car. The chains 22 converge and are attached to the chain or pull rod usually 95 employed for operating the brakes of a railway car; the arrangement of chains 22 being substantially the same as the arrangements of the lower chains shown in Fig. 4 100 of the drawings. The chains 22 are adapted to be wound upon winding surfaces 23 on the drum 17. The drum is formed with a centrally arranged pulley 24, preferably of larger diameter than the diameter of the

- winding surfaces 23. This pulley is engaged by a pull chain 25 in such manner that with an outward pull upon the chain 25 the pulley is caused to roll outwardly on the racks 19. Preferably the chain 25 is anchored to the forward end of member 10, as indicated at 26, and extends around pulley 24 and then over a sheave 27 journaled in a fork 28 at the forward end of member 10, the chain extending upwardly to the power applying device B. In order to keep the chain in place when the brakes are released, an idler roller 29 is journaled in the fork 28 in advance of the sheave 27.
- 15 To the upper end of chain 25 are secured by means of a link or ring 30, a pair of short chains 31 anchored by screws 32 to the winding surfaces 33 formed on a drum 34 having gudgeons 35 extending into vertical guide slots 36 in a housing 37 secured to the end wall of the car. The drum 34 is formed with a pair of gear wheels 38 adapted to mesh with racks 39 formed in the housing 37. The drum 34 is provided with a centrally arranged pulley 40, preferably of larger diameter than the winding surfaces 33 of the drum, and a chain 41 anchored to the housing 37 at 42 extends around pulley 40 and upwardly to a preferably spirally grooved winding drum 42 journaled in a bracket 43 on the upper end of the housing 37. Loosely mounted on the shaft 44 on which the winding drum 42 turns, is an operating lever 45 having pivoted thereto at 46 a pawl 47 adapted to engage the teeth of a ratchet wheel 48 formed on the drum 42. The tail piece 49 of the pawl is heavy enough to maintain an engagement between the pawl and ratchet teeth 48. When the lever is hanging in a vertical position the tail piece 49 of the pawl engages an in-turned lug 50 on a downwardly projecting web 51 formed on bracket 43 so as to effect the disengagement of the pawl from the ratchet wheel. The other end of the winding drum is formed with detent teeth 52 adapted to be engaged by a detent 53 pivoted at 54 to a lug 55 on bracket 43. In place of the detent 53 I contemplate the use of a 50 detent of the character shown in my pending application Serial No. 220,467 filed March 5, 1918.
- In the foregoing description and in the 55 claims appended hereto I use the word "chain" to describe the flexible connecting elements 22, 25, 31 and 41, but it will be understood that ropes or cables might be employed in place of the chains, though perhaps to less advantage. By the word "chain" I intend any suitable flexible connection. Inasmuch as the apparatus as shown and described might be changed in respect to other details of construction, I 60 wish it to be understood that the invention 65 is not to be considered as limited to the

exact arrangements, constructions and devices shown and described, except so far as the claims hereto appended are expressly so limited.

Operation: To set the brakes the trainman, 70 standing on platform D, swings lever 45 toward him in an upward direction. This rotates drum 42, winding chain 41 thereon and thereby causing drum 34 to roll upwardly on racks 39. The rotation and upward movement of drum 34 causes a pull on chains 31, which wind upon the surfaces 33 of the drum and an upward pull is thereupon given to chain 25. This causes drum 17 to roll, outwardly, on the horizontally disposed racks 19 winding chains 22 around surfaces 23 of the drum 17 so as to first take up the slack in the brake connections and then force the brake shoes against the wheels of the car. The taking up of the slack may necessitate several oscillations of lever 45. During these oscillations the winding drum is held by detent 53. The rapidity of the take up in the brake connections is increased by the fact that drums 90 17 and 34 have rolling movements, that is to say, besides rotating they move bodily in the direction to increase the pull on the chains which wind upon them, respectively. The power which may be developed in the actual 95 setting of the brake shoes against the wheels is increased by the fact that pulleys 24 and 40 are of larger diameter than the winding surfaces 23 and 33, respectively, and by the further circumstance that the chains 25 and 100 41 are anchored at their extremities to the car and not to the pulleys. The power is multiplied both by the apparatus on the end of the car and by the apparatus underneath the car. These arrangements are preferred, 105 if not absolutely essential. To release the brakes the lever 45 is raised so as to relieve detent 53 of pressure, whereupon the detent is turned manually about its pivot into position to rest on the bracket 43. The lever 45 110 is then again swung downwardly to bring the tail piece 49 into engagement with the lug 50 for releasing the pawl 47 from the ratchet wheel 48.

I claim:

1. In combination with the brake rigging of a railway car, comprising a take-up chain, apparatus for setting the brakes comprising a drum on which said take-up chain is adapted to wind, and a chain anchored at 120 one end to the car and extending around said drum at a place of larger diameter than the place on which the take-up chain winds for causing the drum to roll in the direction to wind the take-up chain thereon. 125
2. In combination with the brake rigging of a railway car, comprising a take-up chain, apparatus for setting the brakes comprising a drum on which said take-up chain is adapted to wind, a chain anchored at one 130

end of the car and extending around said drum at a place of larger diameter than the place on which the take-up chain winds, a gear wheel on said drum, and a rack with 5 which said gear wheel meshes.

3. In combination with the brake rigging of a railway car, comprising a take-up chain, apparatus for setting the brakes comprising a drum on which said take-up chain is adapted to wind, and a chain anchored at one end to the car and extending around said drum for causing the drum to roll in the direction to wind the take-up chain thereon.

15 4. The combination with the brake rigging of a railway car comprising a take-up chain, apparatus for setting the brakes comprising a drum under the car on which said take-up chain is adapted to wind, a gear wheel on 20 said drum, a rack engaged by the gear wheel, a chain anchored at one end to the car and extending around said drum, to impart rolling movement thereto on the rack, a sheave near the end of the car over which said last 25 named chain passes, and a roller arranged beyond the sheave for retaining the chain in operative position thereon.

5. In apparatus for manipulating the 30 brakes of a railway car, the combination of a supporting structure of channel shape on the under side of the car formed with spaced racks, a drum provided with gear wheels 35 engaging said racks, a pair of winding surfaces of relatively small diameter, and a central pulley of larger diameter, a pair of take-up chains connected with the brake rigging and anchored to and adapted to wind upon said winding surfaces, and a chain engaging said central pulley to roll the drum 40 on said racks.

45 6. In apparatus for manipulating the brakes of a railway car, the combination of a supporting structure of channel shape on the under side of the car formed with spaced racks, a drum provided with gear wheels 50 engaging said racks, a pair of winding surfaces of relatively small diameter, a central pulley of larger diameter, a pair of take-up chains connected with the brake rigging and anchored to and adapted to wind upon said winding surfaces, and a chain anchored at one end to the car and extending around said central pulley to roll said drum on said racks.

55 7. In apparatus for manipulating the brakes of a railway car, the combination of a supporting structure of channel shape on the under side of the car formed with spaced racks, a drum provided with gear wheels 60 engaging said racks, a pair of winding surfaces of relatively small diameter, a central pulley of larger diameter, a pair of take-up chains connected with the brake rigging and anchored to and adapted to wind upon said 65 winding surfaces, a chain anchored at one

end to the car and extending around said central pulley to roll said drum on said racks, a sheave near the end of the car over which said last named chain extends, and a retaining roller arranged beyond said 70 sheave.

8. In apparatus for the manipulation of the brakes of a railway car, the combination of a channel-shaped structure on the under side of the car, the sides of which 75 are formed with slots, spaced racks in said structure, a drum provided with gudgeons to extend into said slots, gear wheels to engage said racks, a pair of winding surfaces of relatively small diameter and a central 80 pulley of larger diameter, a pair of take-up chains connected with the brake rigging, and anchored to and adapted to wind upon said pair of winding surfaces, and a chain engaging said central pulley to roll the drum 85 on said racks.

9. In combination with the brake rigging of a railway car, apparatus for setting the brakes comprising a drum adapted to have a rolling movement in a substantially vertical direction, means providing a connection from said drum to said brake rigging including a chain adapted to wind on said drum, and a chain anchored at one end to the car and extending around said drum to 95 impart an upward rolling movement to the same.

10. In combination with the brake rigging of a railway car, apparatus for setting the brakes comprising a drum adapted to 100 have a rolling movement in a substantially vertical direction, means providing a connection from said drum to said brake rigging including a chain adapted to wind on said drum, and a chain engaging said drum 105 at a place of larger diameter than the place on which the said first named chain winds to impart an upward rolling movement to the drum, said chain being anchored at one end to the car.

11. In apparatus for manipulating the 110 brakes of a railway car, the combination of a vertically disposed housing on the car provided with slots in opposite sides, spaced racks in said housing, a drum formed with 115 gudgeons to extend into said slots, gear wheels meshed with said racks, winding surfaces of relatively small diameter, a centrally arranged pulley of larger diameter, a pair of chains anchored to and adapted to 120 wind upon said winding surfaces, and a chain anchored at one end and extending around said pulley for causing the drum to roll upwardly on said racks.

12. In apparatus for manipulating the 125 brakes of a railway car, the combination of a vertically disposed housing on the car provided with slots in opposite sides, spaced racks in said housing, a drum formed with 130 gudgeons to extend into said slots, gear

- wheels meshed with said racks, winding surfaces of relatively small diameter, a centrally arranged pulley of larger diameter, a pair of chains anchored to and adapted to
5 wind upon said winding surfaces, a chain anchored at one end and extending around said pulley for causing the drum to roll upwardly on said racks, a winding drum for said last named chain provided with a de-
10 tent, a ratchet wheel, and a lever having a pawl to engage said ratchet wheel.
13. In apparatus for the manipulation of the brakes of a railway car, the combination of a chain forming a part of the brake rigging of the car, a drum on which said chain winds, a chain to impart a rolling movement
15 for said last named chain.

movement to said drum, a second drum on the car wall on which said second named chain winds, and a chain to impart a rolling movement to said second named drum. 20

14. In apparatus for the manipulation of the brakes of a railway car, the combination of a chain forming a part of the brake rigging of the car, a drum on which said chain winds, a chain to impart a rolling movement 25 to said drum, a second drum on the car wall on which said second named chain winds, a chain to impart a rolling movement to said second named drum, and a winding drum for said last named chain.

AUGUSTUS F. KLASING.
